CLAIM

The ornamental design for a lightning deterrent, as shown and described.

DESCRIPTION

FIG. 1 is a front perspective view of a lightning deterrent showing my new design;

FIG. 2 is a side elevational view thereof;

FIG. 3 is a top plan view thereof;

FIG. 4 is a bottom plan view thereof;

FIG. 5 is a perspective view of a second embodiment thereof; and,

FIG. 6 is a reduced perspective view of both embodiments thereof, with the articles shown in use, and with the broken line showing for illustrative purposes only and forming no part of the claimed design.

*Fig. 1**Fig. 2**Fig. 3**Fig. 4**Fig. 5**Fig. 6*
